Primary Examiner — Mark A Goodwin*Assistant Examiner* — Harold E Blackwell, II(74) *Attorney, Agent, or Firm* — CANTOR COLBURN LLP(57) **CLAIM**

The ornamental design for a prefabricated angle connector, as shown and described.

DESCRIPTION

FIG. 1 is a perspective view of a prefabricated angle connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the portion 8 of FIG. 1.

The broken lines illustrate portions of the prefabricated angle that form no part of the claimed design.

1 Claim, 7 Drawing Sheets(56)
